APPARATUS FOR PROCESSING SHEET MATERIAL

Ellwood W. Wolf, Philadelphia, and Elbert A. Corbin, Jr., Lansdowne, Pa., assignors of one-third to B. C. B. Industries, a corporation of Delaware

Application September 21, 1940, Serial No. 357,676

1 Claim. (Cl. 91—55)

There is now a great and growing demand for sheet material having a glossy, water-proof and lustrous surface, such material being of paper, fabric, composition, or the like, and has many uses such as menus, book covers, table tops, display cards, merchandise labels, etc.

Our invention relates to an improvement in an apparatus for processing such sheet material to impart thereto a very high grade gloss in an inexpensive and efficient manner.

Our invention further relates to an apparatus whereby continuous and substantially automatic operation is attained whether the sheet material being treated consists of a continuous roll or of separate pieces.

Our novel apparatus will be more clearly understood from the following specification and the accompanying drawing in which:

Fig. 1 represents, diagrammatically and in cross-section, the device embodying our invention by means of which our invention is carried out, the same being shown as adapted to the treatment of piece work.

Fig. 2 represents a view similar to Fig. 1 showing the apparatus used for carrying out our invention as applied to a continuous roll of the material to be treated.

Referring to the drawing in which like reference characters indicate like parts, 4 designates a platform which is reached by the steps 6. On the platform 4 is mounted a work table 8 from which the pieces 10 of sheet material to be treated are fed between the drum 12 and the rollers 14 and 16. 18 designates a trough containing the coating composition 20 and it will be seen that the roller 16 dips into the coating 20 so as to coat the under surface of the sheet material 10 during its passage between the roller 16 and the drum 12. The coating apparatus thus far described and diagrammatically illustrated may be of any satisfactory make now available on the market such as the well known Chambers coating machine. Since the coating machine is conventional, it need not be described in detail. In order to transfer the coated sheet material, from the drum 12 onto the endless conveyor 20, the drum 12 is provided with an opening 13 which accommodates the ends of the lifting bridges or fingers 21 disposed in the plane of the conveyor 20 and tangent to the drum 12. The conveyor 20 is of a mesh or foraminous structure and travels on the rollers 22 and over the vacuum, apertured transfer roller 24. The drying chamber 26 is heated by any suitable means 27. After leaving the vacuum roller 24, the conveyor

20 and sheet material 10 passes under the guide roller 28. The sheet material 10 adheres to the drum 30 and the conveyor 20 passes over the guide roller 32 and back onto the supporting rollers 22 as clearly shown in Fig. 1. At the end of the drying chamber 26 is a flash oven 31 which houses the heating elements 33. The flash oven 31 registers with the upper portion of the drum 30. 34 designates a housing which extends from the flash oven 31 and which encloses the major portion of the drum 30 and the cooperating pressure rollers 36. 40 designates idle or supporting rollers, and 42 designates a vacuum, apertured take-off roll from which the sheet material is removed by the lifting bridges or fingers 44 onto the receiving table 46.

The operation is as follows:

After leaving the drum 12 the coated sheet material is passed through the drying chamber 26 where the volatile solvents of the coating composition are evaporated. To this end the rate of travel, the length of the drying chamber, as well as the temperature therein, are all properly coordinated. When the volatile solvents are evaporated, the residue of the coating composition remains on the surface of the sheet material 10 and the sheet material 10 now enters the flash oven 31 where much more intense heat is applied for a relatively short time so that the intense heat acting on the surface of the evaporated composition on the sheet material 10 serves to fuse the composition or the coating or at least the surface thereof. The sheet material 10 now reaches the vacuum transfer roller 24 where the suction created within the roller and acting through the foraminous conveyor 20 on the sheet material 10 compels the latter to conform to the contour or periphery of the roller 24 thus feeding the leading edge of the sheet material 10 between the roller 24 and the drum 30. The conveyor 20 and the sheet material 10 then pass under the roller 28 after which the sheet material 10 adheres to the drum 30 while the conveyor 20 passes over the guide roller 32 and back onto the supporting rollers 22. The sheet material is now calendered and pressed between the drum 30 and the pressure rollers 36. It will be noted that the extension housing 34, extending downwardly from the flash oven 31 and enclosing the major portion of the drum 30 and the pressure rollers 36, serves to conserve the heat of the flash oven and retain the work pieces 10 at the desired temperature during the pressing operation between the drum 30 and the rollers 36. After passing the pressure rollers 36, the

sheet material 18 travels between the drum 30 and the idle guide or support rollers 40 until it reaches the apertured, vacuum take-off roller 42 which acts in the same manner as the transfer roller 24. In other words, the suction created through the vacuum take-off roller 42 lifts the sheet material off the drum 30 where it is engaged by the lifting fingers or bridges 44 which are carried by or positioned adjacent the work-receiving table 46. The drum 30 is supported by any suitable journal or shaft 48. The rollers 40 are preferably made hollow as at 41 so as to receive a refrigerating medium such as ice water or the like for the purpose of chilling the work pieces 10 after they have emerged from between the last of the pressure rollers 36 and the drum 30. This cooling of the sheet material helps in peeling it off the drum 30 without any damage to the gloss imparted to it by the action of the flash oven and the pressure between the drum 30 and the rollers 36.

In Fig. 2 we have shown substantially the same apparatus for the treatment of continuous sheet material. In this construction, instead of the feed table 8, the sheet material 50 which is in a continuous roll is fed from the feed roll 52 into any suitable coating machine. Since the sheet material is continuous, there is no need for the endless conveyor 20, and the sheet material travels directly over the guide rollers 22. Also, in lieu of the vacuum transfer roller 24 we now use an ordinary transfer roller 54 which deflects the sheet material to bring it into contact with the pressure drum 30 and subject it to the pressure of the rollers 36. Also, due to the fact that the sheet material 50 is continuous, there is no need for the guide rollers 40—unless it is desired to apply refrigeration. The sheet material 50 is wound directly from the drum 30 onto the take-off roll 56. The operation of the form of construction shown in Fig. 2, except for the minor differences in structure pointed out, is substantially the same as that described in connection with Fig. 1.

It will thus be seen that in the construction shown in Fig. 1 the operation is substantially au-

tomatic and continuous and that in the construction shown in Fig. 2 the operation is entirely automatic and continuous. In connection with the construction in Fig. 1, any suitable feeding mechanism can be employed to deliver the sheets 10 into the conventional coater and similarly an automatic take-off mechanism could be employed for stacking work on the receiving table 46. It will also be seen that the essence of 10 our invention resides in successively and continuously applying the desired composition, evaporating the solvents, fusing the surface of the residue and then subjecting the fused surface, while still at the desired temperature, to pressure between the polished surface of the drum 30 and rollers 36, with or without using refrigeration in the rollers 40. Also by making the flash oven 31 as an extension of the drying chamber 26 and by positioning the drum 30 and 15 rollers 36 immediately under the flash oven and enclosing them with an extension 34 of the flash oven, great conductiveness is achieved and all 20 loss of heat is prevented.

Having thus described our invention, what we 25 claim as new and desire to secure by Letters Patent is:

An apparatus for processing sheet material comprising a coating machine for applying the desired glazing compound to said sheet material, 30 a drying chamber for evaporating the solvents of said compound, means for propelling said sheet material through said coating machine and said drying chamber, a flash oven at the end of said drying chamber for fusing the surface of 35 the residue of said compound, a drum having a highly polished surface positioned at the discharge end of said flash oven, pressure rollers coating with said drum, means for bringing the coated surface of said sheet material into contact 40 with the polished surface of said drum and a housing extending from the flash oven and enclosing a portion of said drum and said pressure rollers.
